J. M. HURD,
MACHINE FOR MAKING FLOUR SACKS.

No. 43,773.

Patented Aug. 9, 1864.

UNITED STATES PATENT OFFICE.

J. M. HURD, OF AUBURN, NEW YORK.

MACHINE FOR MAKING FLOUR-SACKS.

Specification forming part of Letters Patent No. 43,773, dated August 9, 1864.

To all whom it may concern:

Be it known that I, J. M. HURD, of the city of Auburn, in Cayuga county and State of New York, have invented a new and useful Machine for the Manufacture of Flour-Sacks; and I do hereby declare that the following is a full, clear, and exact description of the same, reference being had to the accompanying drawings, and to the letters of reference marked thereon.

The object of this invention is for the purpose of facilitating the folding in of the lower corners of the common square-bottom sack, so as to relieve the same from the objection to which that is liable.

In the accompanying drawings the full machine is represented with all its parts in proper place, with a sack drawn over the top thereof, and shown in dotted lines, the bottom of the sack lying flat on the two leaves A and B, with the corners projecting and terminating at C and D. The leaves A and B are jointed to the upright E and F at G and H. The two connecting-rods I and J, the upper parts of which are shown in dotted lines, are jointed to the leaves A and B, the rod I to the leaf A, and the rod J to the leaf B, and both rods are jointed to the levers K and L. The lever K

is mortised through the post E, and is jointed thereto by a pin, (shown at M,) which passes through both the post E and lever K.

Now, the operation of the machine is this: When the sack is placed upon the two leaves, as above described, the triangular pieces represented at N C O and P D Q are pasted on the outer edges, and folded over onto and occupy the space included in the triangular spaces N O R and P Q S, and while held in that position by the hand the feet are placed upon the treadle K, and the two leaves A and B are caused to close together, and the sack is raised for the stand complete.

Having thus described the construction and operation of my invention, what I wish to secure by Letters Patent is—

1. The two leaves A and B, or their equivalents, substantially as and for the purpose specified.
2. The combination of the two leaves A and B with the lever K, substantially as above specified.

J. M. HURD.
